UNITED STATES PATENT OFFICE

FREDERIC R. C. BOYD, OF BOSTON, MASSACHUSETTS, ASSIGNOR TO THE DE LAVAL
SEPARATOR COMPANY, OF NEW YORK, N. Y., A CORPORATION OF NEW JERSEY

OIL-PURIFYING MEANS FOR TURBINES, ETC.

Application filed February 24, 1928. Serial No. 90,289.

The object of my invention is to provide a simple means for continuously purifying lubricating oil that is maintained in circulation through the bearings of a turbine, internal combustion engine, or other engine or motor.

It is known to provide means for centrifugally purifying such oil. Ordinarily a drain tank or settling tank is arranged in the endless oil circulating system and oil is bypassed from such tank through a centrifuge and is thence returned to the tank, or to another tank in the system. It is also known to locate such a centrifuge within a casing carried by the engine and to drive the centrifuge from the engine shaft, the oil being pumped from the tank to the centrifuge and thence forced into and through channels to the bearings.

My invention embodies the known feature of a centrifuge located within a casing formed in or on the turbine or other engine and driven from the shaft.

My invention, however, involves other important features necessary to efficiency, some of which seem to be essential to successful operativeness and all of which are either necessary to, or promotive of, a high degree of efficiency. Such essential and preferable features may be enumerated as follows:

The oil to be centrifuged is led from the bearings, or from the oil supply thereto, to the centrifuge and the purified oil is led to the oil reservoir or tank in the endless circulatory system. No pump is required other than the regular pump for pumping oil through the system. Provision is made for the distribution of the oil uniformly throughout the peripheral part of the centrifuge so as to avoid the likelihood of discharging a substantial proportion of the heavier constituents (water and other impurities) with the oil. Provision is made for insuring the building up of the peripheral wall of the heavier constituents before the discharge of the same from the centrifuge, thereby insuring against the discharge of any of the oil with the heavier constituents. In other words, provision is made for thorough separation before release of the separated constituents and for

insuring against any of the oil being carried off with the water, etc. The casing in which the centrifugal purifier is contained is provided with a partition, thus dividing the casing into two chambers, in one of which the centrifuge is mainly contained and into which the water, etc., is discharged, the oil being discharged into the other and smaller chamber. The invention does not contemplate the purification of all the oil in circuit, some of the oil flowing from the bearings to the oil reservoir and some of it being bypassed from the bearings, or the oil supply thereto, to and through the centrifugal purifiers.

A preferred embodiment of the invention is shown in the accompanying drawing, in which the purifying means is arranged at the end of a turbine shaft, the drawing showing the end bearing of a turbine and the purifying means in vertical section.

The frame *a* carrying the bearing for the end of the turbine shaft *b* is provided with a port *d* communicating with an oil supply pipe *c*. The shaft *b* has a peripheral groove *e* that registers with port *d* and receives oil therefrom. The oil lubricates the bearing by flowing laterally in opposite directions until, near the opposite ends of the bearings, it flows into an annular groove *f* in the bearing. Thence the oil flows through a port *g* into an oil reservoir *h* formed in the hollow base of the bearing frame. Reservoir *h* has an outlet *i* from which the oil is pumped into the oil supply pipe *c* and into other similar pipes for conveying oil to other bearings. The oil from such other bearings finds its way into a pipe *j*, which returns the oil to the reservoir. There is nothing novel in the oil circulating system.

The end of frame *a* is extended to form an open-ended hollow casing *k*. Within the casing, near its outer end, is a partition *m* having a central opening and a flanged edge *m'*, which is confined against an annular shoulder on the inside of casing *k* by means of a flange *n'* on an end cap or closure *n*. The closure *n* is applied to the casing *k* by a screw-threaded engagement between the outer wall of flange *n'* and the inner wall of the casing.

The centrifugal purifier bowl comprises a base o and a body p, p' . The base o has a hub r and a hub extension s which is screw-threaded into a recess in the center of the end of shaft b . When extension s is fully threaded into this recess, hub r abuts against the end of shaft b .

The body of the purifier bowl comprises a peripheral wall p and an end or top p' having a wide central opening. Within and secured to the bowl, and relatively near to its base, and extending parallel to and spaced from the base, is a distributing disc t . The disc is imperforate and is of somewhat less diameter than the inner diameter of the bowl so as to leave an annular opening between its periphery and the bowl wall.

Within and secured to the bowl, and relatively near its top p' and spaced therefrom, is a top disc u having a neck v . Disc u is imperforate and is of somewhat less diameter than the inner diameter of the bowl so as to leave an annular opening between its peripheral edge and the bowl wall. Neck v extends through the wide central opening in the bowl top p' and also through the central opening in the partition m . The central opening in top p' is of substantially greater diameter than neck v , so as to provide an unobstructed annular passage around the neck between it and the bowl top. Neck v has as close a fit in partition m as is permissible, bearing in mind that one member is rotatable and the other stationary.

Shaft b is provided with an axially extending channel w , which is prolonged through the bowl hub and base and communicates with the distributing space within the bowl between its base o and distributing disc t . By means of a radial channel w' , some of the oil fed into groove e is by-passed to the purifying bowl. Channel w may be prolonged along the length of the shaft and may communicate with other bearings, thereby connecting any bearing or all bearings with the purifying means.

By means of partition m , casing k is divided into a large compartment x enclosing the bowl and spaced therefrom on all sides and communicating with the peripheral part of the bowl, and a small end compartment y communicating with the central part of the bowl through the neck v . A pipe z connects compartment y with reservoir h , and a pipe g acts as a drain for compartment x .

Oil passing toward the bearing a will divide into two streams, one passing between the shaft b and the bearing and the other flowing through the central channel w in the shaft and bowl hub to the interior of the bowl o, p, p' . Distributing disc t compels all the oil to flow to the peripheral part of the bowl. There, under the influence of centrifugal force, the heavier impurities in the oil, which will usually consist mainly of water, will be

forced toward, or remain at and near, the periphery and will displace the oil inwardly toward the bowl center. Owing to the disc u , a peripheral wall of water will build up within the bowl and insure against the outflow of any oil with the water. The water, after it has accumulated and formed a thick peripheral zone, will be forced around the inside periphery of the bowl top p' and into the water chamber x of casing k . The oil that is displaced toward the center of the bowl flows out the neck v into the oil chamber y of casing k and thence escapes, through pipe z , to reservoir h .

Having now fully described my invention, what I claim and desire to protect by Letters Patent is:

1. In a lubricating oil system for turbines and other engines, the combination with a shaft bearing, a shaft turning in said bearing and having an oil channel communicating with the bearing, a centrifugal purifier carried on the shaft and communicating with said channel, means, including a reservoir, adapted to supply oil to the shaft bearing, and a casing enclosing the purifier; of a partition in said casing, the purifier having an outlet communicating with the central part of the purifier and with the casing on one side of the partition and an outlet communicating with the peripheral part of the purifier and with the casing on the other side of the partition, and means affording a passage for purified oil between the casing on the first named side of the partition and the reservoir.

2. In a lubricating system for turbines and other engines, the combination with a shaft bearing, a shaft turning therein and having an oil channel communicating with the bearing, means to supply oil to the shaft bearing, a centrifugal purifier carried on the shaft, and a casing enclosing the purifier; of a partition in said casing dividing it into two chambers, the body of the purifier being contained in one chamber, the purifier having an inlet communicating with the shaft channel, an outlet communicating with its peripheral portion and with the chamber in which the body of the purifier is contained, and an outlet communicating with its central portion and with the other chamber.

3. A lubricating system in accordance with claim 2 in which the means for supplying oil to the shaft bearing comprises an oil reservoir, and comprising also a pipe connecting the last named chamber and the reservoir.

4. In a lubricating system for turbines and other engines, the combination with a shaft bearing, a shaft turning therein and having an oil channel communicating with the bearing, means to supply oil to the shaft bearing, a centrifugal purifying bowl carried on the end of the shaft and having an oil inlet in one end communicating with the oil channel

in the shaft, and a casing enclosing the bowl; of a partition in the casing on one side of which the bowl is positioned, a distributor in the purifier relatively near its base and 5 adapted to convey oil from said inlet to the periphery of the bowl, and a disc relatively near the other end of the purifier having a neck extending through and spaced from a discharge orifice in the bowl and extending 10 also through the partition.

5. In an oil purifying system for turbines and other engines, the combination with the main shaft, a stationary frame carrying a shaft bearing, an oil reservoir, and means to 15 circulate oil from the reservoir through said bearing and back to the reservoir; of a bypass for oil comprising a channel extending longitudinally within the shaft, a casing carried by the shaft bearing, a pipe connecting 20 the casing and reservoir, and a centrifugal purifier on the end of the shaft within the casing and having an oil inlet communicating with said channel and a purified oil outlet communicating with said casing.

25 In testimony of which invention, I have hereunto set my hand, at Trenton, New Jersey, on this 10th day of February, 1926.

FREDERIC R. C. BOYD.
